UNITED STATES PATENT OFFICE.

CHARLES T. HAWLEY, OF HOLDEN, MASSACHUSETTS, ASSIGNOR TO WORCESTER
PRESSED ALUMINUM COMPANY, A CORPORATION OF MASSACHUSETTS.

CAN OPENER.

Application filed January 9, 1922. Serial No. 527,841.

To all whom it may concern:

Be it known that I, CHARLES T. HAWLEY, a citizen of the United States, residing at Holden, in the county of Worcester and State of Massachusetts, have invented a new and useful Can Opener, of which the following is a specification.

This invention relates to a can opener of the type in which the edge or rim of the can is severed by means of a rotary disc cutter.

It is the general object of my invention to provide an improved device of this description which is simple in construction, economical in manufacture and which is efficient and satisfactory in use.

With this general object in view, an important feature of my invention relates to the provision of a can opener in which the cutter is free to revolve independently of the feed wheel or wheels with which it is associated.

Other features of my invention will be hereinafter described and more particularly pointed out in the appended claims.

A preferred form of the invention is shown in the drawings, in which—

Fig. 1 is a plan view of my improved can opener;

Fig. 2 is a side elevation thereof;

Fig. 3 is a partial plan view with the parts in a different position; and

Figs. 4 and 5 are detailed sectional views taken along the lines 4—4 and 5—5 in Fig. 3.

Referring to the drawings, I have shown a can opener comprising a pair of levers or handles 10 and 11 pivotally secured to each other by a rivet or other fastening device 12. A feed roll 13 is fixed to a headed stud 14 which extends freely through the end of the handle 10, the roll being thus freely rotatable upon the handle.

A bearing 15 is formed on the end of the handle 11 and a shaft 16 is rotatably mounted in the bearing 15. A bushing 17 is secured on the outer end of the shaft 16. A disc cutter 18 is freely rotatable on the bushing 17 and a feed wheel 19 is closely

fitted thereon. A cross pin 20 extending through the feed wheel 19, the bushing 17 and the shaft 16 secures these parts firmly together but permits free rotation of the disc cutter 18.

A collar 21 on the shaft 16 prevents longitudinal movement of the shaft in the bearing 15 and a handle 22 secured to the outer end of the shaft provides for manual rotation thereof.

In the use of the device the edge of a can C is grasped between the feed rolls 13 and 19, the disc 18 being at the same time forced against the side of the can. The feed roll 19 is then rotated by means of the handle 22, moving the can past the cutter 18, which severs the top of the can from the body portion thereof. As the cutter 18 is free to rotate by contact with the can the difference in diameter of the cutter 18 and feed roll 19 does not cause the cutter to be dragged through the can at a speed faster than the movement of the can surface would require.

Having thus described my invention, I do not wish to be limited to the details herein disclosed otherwise than as set forth in the claims, but what I claim is:—

1. A can opener having, in combination, a pair of pivoted handles, a feed roll mounted on one of said handles, a co-operating feed roll rotatably mounted upon the second handle, manual means to rotate the latter feed roll, and a disc cutter mounted for free rotation about the axis of said latter feed roll.

2. A can opener having, in combination, a pair of pivoted handles, a feed roll mounted for free rotation on one of said handles, a bearing on the second handle, a shaft rotatably mounted in said bearing, a handle for said shaft, a feed roll fixed to said shaft and rotated therewith, and a disc cutter mounted to rotate about the axis of said shaft and freely rotatable relatively to said shaft and its associated feed roll.

In testimony whereof I have hereunto affixed my signature.

CHARLES T. HAWLEY.
